United States Patent Office

Des. 192,999
Patented June 12, 1962

192,999

FURNITURE BASE

Allan J. Hastings, Wichita, and Edward C. Julian, Lawrence, Kans., assignors to The Boeing Company, Wichita, Kans., a corporation of Delaware

Filed June 2, 1961, Ser. No. 65,433

Term of patent 14 years

(Cl. D15—1)

FIG. 1

FIG. 2

FIG. 3

FIG. 4

FIGURE 1 is a perspective view of a furniture base embodying our design.

FIGURE 2 is a front view of the furniture base.

FIGURE 3 is a side view of the furniture base.

FIGURE 4 is a bottom view of the furniture base.

The dominant features of our design reside in those portions shown in full lines on the drawing.

The design is characterized by a broad cone joined midway on its sides by relatively long slender legs at approximate right angles to the cone surfaces they meet, all as shown.

We claim:

The ornamental design for a furniture base, as shown and described.
